UNITED STATES PATENT OFFICE.

JOHN R. GAMMETER, OF AKRON, OHIO, ASSIGNOR TO THE B. F. GOODRICH COMPANY, OF NEW YORK, N. Y., A CORPORATION OF NEW YORK.

VULCANIZING-PRESS.

1,232,022.

Specification of Letters Patent.

Patented July 3, 1917.

Application filed April 18, 1917. Serial No. 163,043.

To all whom it may concern:

Be it known that I, JOHN R. GAMMETER, a citizen of the United States, residing at Akron, in the county of Summit and State 5 of Ohio, have invented certain new and useful Improvements in Vulcanizing-Presses, of which the following is a specification.

This invention relates to presses adapted to operate upon a series of molds arranged 10 in a vertical tier, for vulcanizing rubber goods. The object of the invention is to provide an improved elevator and platform mechanism and so to combine the same with the press as to facilitate the placing of 15 molds in position within the press and their removal after their contents have been vulcanized.

Of the accompanying drawings,

Figure 1 represents an end elevation of 20 a six-compartment hot-plate vulcanizing press provided with platforms and elevator mechanism constructed and arranged according to my invention.

Fig. 2 represents a top plan view thereof, 25 partly broken away.

Fig. 3 represents a side elevation partly in section on the line 3—3 of Fig. 2.

In the drawings, 10 is a hydraulic cylinder forming the base of the press and provided with bosses 11 which are connected by vertical bolted tie-rods 12 with similar bosses 13 upon a stationary head or platen 14. In 30 the cylinder 10 is a piston or ram 15 which works through a stuffing-box 16 and carries 35 at its upper end a movable platen or press plate 17.

There is provided a series of seven hot-plates 18, here shown conventionally but having any suitable internal construction for 40 distributing the heating fluid and withstand- 45 ing its pressure, the uppermost plate being affixed to the upper platen 14, while the lower one rests upon the movable platen 17. The intermediate plates have varying de- 50 grees of vertical movement corresponding to their respective distances from the top platen. For arresting each of the several intermediate hot-plates 18 at a predetermined distance below the plate above it, and thus 55 uniformly deepening or opening the mold compartments between the plates to permit the insertion and withdrawal of the molds.

when the lower platen is depressed, each of said intermediate hot-plates is provided near its corners with four pins 19 engaging suitable stops or abutments at the bottoms of a series of recesses 20 and slots 21 formed in a set of four vertical stop-plates 22, the pins being guided in their vertical movements by the sides of the slots and recesses, and the 60 latter being of progressively increasing length, downwardly of the series.

23 is a steam inlet manifold having a pressure-gage 24 and fed by a supply pipe 25, said manifold being connected by a series of 65 looped flexible branch pipes 26 with the respective movable hot-plates 18, and connected by a rigid branch pipe 26^a with the uppermost or fixed one of said plates. A similar manifold 27 leading to a discharge pipe 70 128 is connected by flexible and rigid branches 28, 28^a with the said movable and fixed hot-plates 18 on the opposite side of the press from the inlet manifold.

On the other two sides of the press the 75 six compartments 29 formed between the seven hot-plates 18 are open or exposed horizontally at their ends for the full width of said plates, and I provide on these two sides a pair of parallel elevator platforms 30 mounted upon a frame composed of short and long longitudinal U-beams 31, 32 and long transverse U-beams 33. The edges of the platforms are convexly rounded as shown at 34 so as to facilitate the sliding of 80 the molds onto and off of the platforms without catching, and the inner edges of said platforms are located close to the tier of hot plates. Each platform is of such length as to extend beyond the tier of hot plates at 85 both ends so as to support the molds both in front of and at either side of said tier. One of the molds 35 is shown on the left-hand platform in Fig. 1.

36 is a vertical hydraulic cylinder mounted on top of the fixed upper head or platen 14 and containing a ram or piston 37 which works through a stuffing-box 38 at the upper end of said cylinder. The piston 37 carries at its upper end a four-arm yoke 39 from 90 the ends of whose arms the platform structure is suspended by four vertical rods 40 bolted at their lower ends to the inner ends of the beams 31. These rods are guided in

bosses 41 formed on the platen 14, and the yoke 39 is provided with a pair of additional guide-rods 42 working in guide-bosses 43 on the upper rim of the cylinder 36.

- 5 For raising and lowering the two pistons, there are provided suitable controlling valve devices 44, 45 actuated by hand-levers 46, 47 and located on opposite sides of the press so that each is within convenient reach of one 10 of the two attendants. 48 is a trunk supply pipe leading from a suitable source of hydraulic pressure and connected by branch pipes 49, 50 with the casings of the respective valve mechanisms. Pipes 51, 52 lead 15 from the respective valve casings to the respective cylinders 10 and 36, and waste pipes 53, 54 lead away from the valve casings, the arrangement being such that by manipulation of the hand-lever 46 or 47 either cylinder 20 may be charged or discharged at will as will be readily understood.

The press is opened by discharging the lower cylinder 10 and allowing its piston to descend by gravity with the movable platen 25 17, thus opening the mold compartments 29 and permitting the molds to be inserted in or removed from said compartments. When the desired number of molds is in place, the water pressure is admitted to said cylinder 30 in order to raise the lower platen, together with the molds and the movable hot-plates 18, and place the molds and their contents under pressure while vulcanization is effected by the heat of the steam in the hot- 35 plates. When the press is opened and the molds are to be changed, the hand-lever 47 is manipulated so as to charge or discharge the upper cylinder 36 and bring the platforms 30 opposite to or in registry with the bottom or floor of the desired compartment, and the exchange is then effected by the operator on one side pushing a fresh mold into the compartment and thereby pushing out a cured mold onto the opposite platform 40 45 where it is received by the operator on that side. The press may be operated by curing the full complement of molds all at the same time, but I prefer the mode of operation described in my companion application Serial No. 163,042 filed concurrently herewith, according to which the press is kept full, but the molds are cured in pairs with overlapping curing periods, only two of the molds being changed at any one time, and the 50 others being allowed to remain in the opened press during the exchange. Each operator has a fresh mold ready when the press is opened. The operator on the right, for example, will use his fresh mold to push out a 55 cured mold, say from the uppermost compartment, to the operator on the left, who slides it to one side on his platform while the platforms are being lowered to the next compartment, and with his fresh mold in 60 65 front of this compartment he pushes out the

second cured mold to the operator on the right, after which the press is closed and the foregoing operations are thereafter repeated upon succeeding pairs of molds as their curing periods mature, the operators in the meantime being occupied by emptying and refilling the two spare molds which have just been withdrawn from the press.

I claim:

1. In combination, a vulcanizing press 75 adapted to operate upon a series of molds arranged in a vertical tier, platforms on opposite sides of said press, and means for raising and lowering said platforms.

2. In combination, a vulcanizing press 80 adapted to operate upon a series of molds arranged in a vertical tier, platforms on opposite sides of said press, and means for simultaneously raising and lowering said platforms.

3. In combination, a vulcanizing press 85 of the hot-plate type having a tier of mold compartments, a pair of platforms located at the same level, adjacent to and on opposite sides of said tier and connected to 90 rise and fall in unison, for successively registering with the several compartments, and means for raising and lowering said platforms.

4. In combination, a vulcanizing press of 95 the hot-plate type having a tier of mold compartments, elevating means mounted over said tier, and a pair of platforms suspended on opposite sides of said tier and actuated by said elevating means.

5. In combination, a vulcanizing press 100 having an upper fixed platen, a vertical hydraulic cylinder mounted thereon and having a piston working through its upper end, a lower hydraulic cylinder having a piston, 105 a movable platen actuated thereby, a series of hot-plates forming a tier of mold compartments between said platens, and a pair of platforms suspended on opposite sides of said tier and adapted to be raised and lowered 110 by the upper piston.

6. In combination, a vulcanizing press having an upper fixed platen on which is mounted a vertical hydraulic cylinder, a piston working through the upper end of 115 said cylinder and carrying a yoke, a pair of platforms on opposite sides of the press suspended by rods from said yoke, a lower hydraulic cylinder and piston, a movable platen actuated thereby, and a series of hot- 120 plates forming a tier of mold compartments between said platens, with which the platforms are adapted successively to register.

7. In combination, a vulcanizing press 125 having a tier of hot-plates forming mold-receiving compartments, and an elevator platform having means for raising and lowering it to register successively with the several compartments, said platform extending in front of and laterally beyond the 130

tier so as to accommodate molds both in front of and at the side of said tier.

8. In combination, a vulcanizing press having a tier of hot-plates forming mold-receiving compartments, a pair of platforms located at the same level on opposite sides of the tier, said platforms extending in front

of and laterally beyond the tier, and means for raising and lowering said platforms in unison.

10 In testimony whereof I have hereunto set my hand this 16th day of April 1917.

JOHN R. GAMMETER.
